SHEET FOR LOOSE-LEAF BOOK PAGES

William P. Pitt, Union, N. J.

Application March 1, 1944, Serial No. 524,569

2 Claims. (Cl. 129—1)

This invention relates to paper sheets for loose leaf book pages, which have perforations or holes therethrough spaced along the margins to receive the binding rings or pins of a binder.

Frequently the paper sheets are too thin and weak or are roughly handled so that they become worn or torn by frictional contact with the binder rings or studs at the edges of said binding perforations. Many attempts have been made to reenforce such sheets against such wear and tear.

Heretofore, flat rings or strips of cardboard or fabric or metal have been applied to the sheets around the holes by being embedded in the sheets, either by cutting away the sheet to receive the ring or strips, or by pressing the flanges of metal eyelet into the paper so that the exposed surface of the reenforcing element is flush with the surface of the sheet, whereby to obviate bulging of a pile of the sheets along the binding margin that would occur if the reinforcements projected above the surfaces of the sheets. These structures are costly and in effect defeat their purpose, because the sheets must be thick enough to receive the embedded reenforcing element and the thicker the sheet the less the need for the reenforcement. Moreover, the eyelet is rigid and easily is torn out of the sheet.

Another proposal has been the superficial application adhesively to the sheet of metal foil reenforcing elements so thin that they do not increase substantially the combined thicknesses of the sheet and one of said elements is not substantially greater than the thickness of the sheet alone. This structure fails to completely solve the problem because it is limited to unusually thin sheets, and the reenforcing element is thin and is exposed at its edges which makes it liable accidentally to be torn or distorted itself or to be pulled off the sheet.

Therefore a prime object of my invention is to provide a reenforced sheet of the general character described which shall overcome the objection to and disadvantages of the known sheets, which shall be simple and inexpensive and shall reduce substantially the injury to said sheet from wear and tear at the binding holes.

Another object is to provide such a loose leaf book page wherein the reenforcing element shall be embedded in the paper sheet without cutting away of the sheet and without increasing the combined thickness of the sheet and the reenforcing element.

Other objects are to provide a novel and improved method of applying a reenforcing element

to a paper sheet such that the edges of the element shall be located below the surface of the sheet and the paper beneath the element shall be inherently strengthened to complement the

element and reenforce it against distortion from bending; and to obtain other results and advantages that will be brought out by the following description in conjunction with the accompanying drawing in which

10 Figure 1 is a perspective view of a loose leaf binder sheet having a reenforcement embodying the invention.

Figure 2 is an enlarged transverse vertical sectional view through the sheet on the line 2—2 of Figure 1.

Figure 3 is a fragmentary transverse vertical sectional view through the sheet, metal reenforcement and applying dies for securing the metal reenforcement to the sheet.

20 Figure 4 is a greatly enlarged fragmentary vertical sectional view through a portion of the sheet and a portion of the reenforcing element.

Figure 5 is a fragmentary sectional perspective view of a sheet embodying a modified form of the invention, and

Figure 6 is a fragmentary perspective view of another modified form of sheet.

Specifically describing the embodiment of the invention illustrated in Figures 1 to 4 inclusive, the reference character A designates a sheet of the material to serve as a loose leaf binder sheet. It is desirable that the material of the sheet be fibrous and preferably it is paper. The thickness of the sheet may vary, but generally will be of the order of .004". As usual the sheet has a plurality of perforations or holes therethrough and spaced along one margin to receive the binding rings or pins of a loose leaf binder, and in accordance with the invention, each of the binding holes B is reinforced by a metal reenforcing element C.

The reenforcing elements C preferably are formed of spring sheet steel or metal foil the thickness of which may vary but preferably is of the order of one-quarter of the thickness of the loose leaf sheet to which the element is to be applied. For example, for a loose leaf sheet having a thickness of .004" the reenforcing element would be of a thickness of about .0015".

50 The reenforcing element may be applied to the sheet in several different ways, but preferably a flat disc or wafer of sheet metal 1 is pressed into one side of the sheet, for example by the dies 2 and 3 as shown in Figure 3, with an adhesive or cement, such as a thermoplastic substance im-

posed between the disc and the loose leaf sheet, and so that the exposed surface of the disc is substantially flush with the surface of the fibrous sheet. During this operation the fibers on the surface of the loose leaf sheet are broken and bent and some of the fibers are caused to lie along the edges of the disc, as indicated at 4 in Figure 4. At the same time, the fibers in the portions of the loose leaf sheet between the disc and the opposite side of the sheet are tightly compressed together as indicated at 5 more compactly than elsewhere in the sheet so that said portion of the sheet is strengthened. The adhesive is caused to run along the fibers and thereby firmly attach them to the surfaces of the disc and the fibers at the same time, being embedded in the adhesive, serve as reenforcements therefor. The adhesive will impregnate the fibrous sheet at the edge of the disc on the surface of the sheet and provide a substantially smooth and continuous surface between the sheet and the disc.

Thereafter the binder hole B may be punched through the fibrous sheet A and the metal disc 1 at the same time. During this punching operation a burr 6 may be formed on the underside of the disc at the edge of the hole and the burr may be caused to penetrate the fibrous sheet and become attached to the fibers. Where the disc is originally punched from the sheet, the outer edge of the underside of the disc may have a similar burr 7 which penetrates the fibrous sheet and becomes attached to the fibers as the disc is applied to the sheet.

The metal disc is flexible to permit the desired bending of the sheet at the binder rings or posts and at the same time the disc will effectively protect the sheet at the edges of the binder holes against wear and tear. The compressed portion of the sheet beneath the disc will reinforce the latter to protect it against distortion from bending and the edges of the disc, being embedded in the sheet, are protected against being struck by exterior objects in such a manner as to bend the disc or loosen it from the sheet.

Preferably the adhesive will be thermoplastic and will be heated during the pressing of the disc into the fibrous sheet, and the adhesive has some elasticity to reduce the tendency of the fibrous sheet to pull away from the edges of the disc or vice versa.

If desired, the fibrous sheet A may be punched

first, after which the perforated metal reenforcement can be applied to the sheet; or the binder hole and a recess to receive the reinforcing disc could be formed in the fibrous sheet after which the perforated reenforcing disc could be cemented in the recess. It will also be obvious to those skilled in the art that if desired the recess in the fibrous sheet may first be formed after which the unperforated disc 1 might be cemented in the recess.

A modification of the invention is shown in Figure 5 where the reenforcing element D is a rectangular piece of metal that has a hole 8 in register with the binder hole 9 in the fibrous sheet E.

In Figure 6 is shown a metal strip F extending along the margin of the fibrous sheet G and having a plurality of perforations 10 therein registering with the binder holes 11 in the fibrous sheet G.

Other modifications and changes in the details of construction of the loose leaf binder sheet and the manner of applying the reenforcing element will occur to those skilled in the art as within the spirit and scope of the invention.

What I claim is:

1. A loose-leaf binder sheet having a binder hole and a recess in one side bordering said hole that has been formed by pressing the material of said sheet, and a flat metal foil reenforcing element cemented in said recess with its exposed surface flush with the surface of said sheet and having a burr at its edges penetrating said sheet and attached to the fibers thereof.

2. A fibrous loose leaf binder sheet having a binder hole and a recess in one side bordering said hole, the fibers in the portion of said sheet between the bottom of said recess and the other side of said sheet being compressed together more compactly than elsewhere in the sheet whereby

40 said portion of the sheet is strengthened, a flat metal foil reinforcement seated in said recess with its exposed surface flush with the surface of said sheet, and an adhesive between said element and the walls of said recess, a plurality of fibers projecting from the walls of said recess and running along the edges of said element so that said fibers are firmly secured to said element and said adhesive is reinforced by said fibers extending therethrough.

WILLIAM P. PITTS.
